(57) **CLAIM**

The ornamental design for a beverage bottle with drink-through cap, as shown and described.

DESCRIPTION

FIG. 1 is a front top perspective view of a beverage bottle with drink-through cap, showing our new design with the drink-through cap in a closed position;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top view thereof;

FIG. 7 is a bottom view thereof;

FIG. 8 is a rear top perspective view thereof;

FIG. 9 is a front top perspective view thereof, showing our new design with the drink-through cap in an opened position; and,

FIG. 10 is a rear top perspective view thereof.

The evenly broken lines are shown for the purposes of illustrating the boundaries of the claims as well as parts of the article, none of which form part of the claim.

1 Claim, 9 Drawing Sheets
